UNITED STATES PATENT OFFICE.

JAMES BRAGG, OF ST. JOSEPH, MISSOURI, ASSIGNOR TO SPECIALTY SHOE MACHINERY COMPANY, OF ST. JOSEPH, MISSOURI, A CORPORATION OF MISSOURI.

SHOE-NAILING MACHINE.

1,252,378.

Specification of Letters Patent.

Patented Jan. 1, 1918.

Application filed October 9, 1916. Serial No. 124,554.

To all whom it may concern:

Be it known that I, JAMES BRAGG, a citizen of the United States, and a resident of St. Joseph, county of Buchanan, and State of Missouri, have invented certain new and useful Improvements in Shoe-Nailing Machines, of which the following is a specification.

My invention relates to machines for automatically driving nails into the soles and heels of leather shoes.

One of the objects of my invention is the provision of a chute for the nails that is adapted to convey them from the usual hopper and feed them to the "throat" where they are operated upon by the driving element, said chute being removable so that it may be conveniently detached to remove the nails in the event they become clogged. Another object of my invention is the provision in a shoe nailing machine of an effective means for accurately guiding and controlling the drive arm of a machine where a long drive is essential. Still another object of my invention is the provision in a shoe nailing machine of a driving rod of relatively small diameter that is securely held in position by a suitable removable head whereby it may be readily attached to or detached from the driving arm. A further object of my invention is to provide a nailing machine with a nail throat that is continuous and of the same diameter, from the feeding mechanism to the driving chamber, thereby preventing clogging of the chamber and jamming the driving rod. And a still further object of my invention is the provision of a nail switch (or what is commonly known as a "hopper block") that is effective in feeding the nails separately from the hopper to the nail chute, and which may be automatically locked and prevented from feeding nails in the event the shoe, sole or heel has not been moved or fed to the proper position to receive a nail. Other objects of my invention are to provide a hopper block and associated mechanism that is comparatively inexpensive to manufacture so that it will not add materially to the cost of the shoe-nailing machine; to provide a simply constructed mechanism for feeding nails; and to provide a device that is easy to manipulate.

I prefer to accomplish the divers objects of my invention by the means and in the

manner hereinafter fully described and as more particularly pointed out in the claims, reference being had to the accompanying drawings forming a part of this specification, wherein,—

Fig. 1 is a vertical side elevation of the nailing head of my improved shoe-nailing machine, looking at the side upon which the driving arm is disposed.

Fig. 2 is a fragmentary view of the upper portion of the machine shown in Fig. 1, looking at the same from the opposite side.

Fig. 3 is a fragmentary plan of the top of the machine, certain portions being broken away for clearness.

Fig. 4 is a vertical sectional view through the nail chute and the nail throat or driving head.

Fig. 5 is a vertical section of outer end of the drive-arm, taken at a right angle to Fig. 4.

Fig. 6 is a detail view of the nail-switch actuating device detached from the machine.

Fig. 7 is a detail elevation of the hopper-block and nail-switch, looking at the same from the drive-arm side of the machine and the adjoining elements removed for the purpose of clearness.

Fig. 8 is a plan of the top of the hopper-block and nail switch shown in Fig. 7.

Fig. 9 is a longitudinal horizontal section taken on line 9—9, Fig. 7, looking in the direction of the arrows.

Fig. 10 is an enlarged longitudinal horizontal section taken on line 10—10, Fig. 8, looking in the direction of the arrows.

Fig. 11 is an enlarged longitudinal horizontal section taken on line 11—11, Fig. 8, looking in the direction of the arrows.

Fig. 12 is a perspective view of the nail switching member detached.

Fig. 13 is a perspective view of the locking device detached from the hopper-block.

Referring to the drawings, it will be observed that a suitable raceway or slotted guide 10 is provided with and is preferably inclined from the nail hoppers at the top of the standard of the machine to the hopper block that is adapted to receive the nails therefrom and feed them to the driving mechanism. Secured to or adjacent the wall of the raceway is a suitable block 11 that is substantially rectangular in outline and is provided with a vertically disposed bearing boss 12 that is bored vertically and is dis-

posed opposite the lower end of the raceway 10. This boss 12 provides a bearing for a suitable stem or spindle 13 having its opposite ends extended through said boss and the 5 upper extended end provided with a circular disk 14, the marginal periphery of which projects beyond the boss, as shown, and is provided with a depending apron 15. This apron 15 is curved concentrically with the 10 axis of the spindle 13 and is adapted to move across the adjacent end of the raceway or guide 10, and the boss is provided with a corresponding enlargement 16 to permit of a sufficiently snug fit and prevent the nails 15 from entering the space between said elements. This disk and the apron constitute a nail-selecting or feeding device that is adapted to shunt or carry the nails from the raceway to a position where they will fall 20 by gravity into a proper feed passage 17 and thereby be transferred or fed to the nailing member. The nail-selecting device has a limited movement by providing a pin 18 upon the upper edge of the bearing boss 25 that projects into an elongated, concentric notch or recess 19 formed in the disk 14, the ends of said notch or recess being adapted to serve as stops when abutting the pin 18.

The lower end of the spindle 13, below 30 its bearing has attached thereto an operating lug or arm 20, adapted to be engaged and actuated by suitable mechanism to be hereinafter fully described, whereby the same is given a reciprocatory movement, 35 thus transmitting to the disk 14 an oscillatory motion, the limit whereof is determined by the length of the notch or recess 19 in said disk.

Disposed in alignment with the lower end 40 of the slotted guide or raceway 10, is a small notch 21 in the margin of the disk 14, into which the lowermost nail in the raceway will be fed and be supported in a pendent position by its head, the shank of 45 the nail being disposed adjacent one edge of the depending apron 15, as the notch is formed in the edge of the disk immediately at the side of said apron. When the operating lug or arm 20 is moved and the disk 50 rotated, the nail will be carried by the disk a short distance, where it arrives over the nail-chute or feed-pipe 22 leading to the driving member. A switch-arm or ejector 55 is here adapted to push the nail out of the notch or recess 21 and permit the same to gravitate down into the nail-chute. This switch comprises a suitable integral plate, the body portion 23 whereof being disposed flat upon the top of the block 11 and secured 60 thereto by a suitable set-screw. The outer laterally bent portion 24 of the switch is disposed in a vertically cut slot in said block and the extension or vertical lateral member extends toward the disk. This lateral member 65 comprises two arms 25 and 26, the

former disposed adjacent the upper surface of the disk, and the latter extending parallel thereto and below the under surface of the disk. The upper edge of the lower arm 26 is beveled or inclined, as shown in detail 70 in Fig. 4 of the drawings, so as to insure the nail gravitating and not hanging upon the edge thereof when knocked off the disk.

In order to prevent the disk rotating in the event the feed pipe 22 has been removed, 75 a lock-pin 27 is provided, the vertical portion of which reciprocates in a guide channel 27^a provided in the block and the upper end whereof is looped so that one shoulder formed by said loop may be dropped into 80 the adjacent portion of the notch or recess 19 when the nail notch is opposite the raceway. The looped end is continued upon the opposite side of the block and is carried downwardly past a stud 28 to prevent the 85 rotation of the lock-pin and is then bent laterally beneath said stud 28 to prevent the accidental displacement or withdrawal of the lock-pin. The upper part of the guide-channel 27^a is slotted through to both sides 90 of the block so as to receive the top of the loop when it is in its lowermost or locking position. The lower end of the lock-pin extends down through channel 27^a and rests upon the upper surface of a suitable block 95 40 that is secured in position by a screw or otherwise. The engagement of the lock-pin with the slot in the disk is permitted to take place upon the removal of the block 40 and will prevent the disk being 100 rotated sufficiently to deliver and eject the nail and as soon as the block 40 is replaced the lock-pin 28 will be elevated out of said notch or recess and permit the disk to again be rotated. The nail ejected from the disk 105 14 gravitates through the nail chute 22 and is received into a suitable chamber 30 of the nail throat or sleeve 31, said chamber being continuous and of the same diameter throughout so as to avoid the arresting of 110 the nails therein and the consequent jamming of the chamber. Nail chute 22 is preferably removable and comprises a tube, the lower end being cut obliquely as shown at 41 in the drawing, and is fitted into the 115 outer portion of the sleeve 31, while its upper end extends up into the block 40 so that when the latter is released from its fastenings and removed, said chute may be readily withdrawn. The throat or sleeve 31 120 is bored axially to receive the driver rod 32 which reciprocates therein and engages each nail and drives it into the shoe. This driving rod 32 is of relatively small diameter and has its upper end secured in a suitable 125 cylindrical head 33, the lower end of said head being provided with an annular shoulder 34, and which is preferably bifurcated longitudinally by cutting a suitable kerf 35 axially and longitudinally through the 130

same. A flattened portion 36 is provided upon the exterior of the head that is adapted to be engaged by a suitable locking bolt or screw 37, whereby the driving-rod is frictionally and firmly held in place. By this construction I am permitted to readily replace either the head or the driving-rod in event either becomes broken or bent, and it will be obvious that the change may be readily made by the ordinary mechanic.

The standard 42 of the driving head of the machine is preferably provided with a laterally disposed overhanging arm 43, the outer end whereof is provided with two bosses 44 and 45 that respectively carry the hopper block and the nail throat or sleeve, while adjacent the inner end of said arm 42 is a bearing in which the upper end of a vertically disposed reciprocating actuating rod 46 is mounted, the opposite or lower end of said rod being extended through the base 47 of the head and its lower end connected to suitable actuating mechanism such as a foot treadle or the like (not shown). Rod 46 affords one of the guides and carries the drive-arm that is adapted to reciprocate vertically therewith, said drive-arm preferably comprising a suitable sleeve or bearing boss 48 that surrounds said rod, from which extends an elongated upwardly inclined arm 48^a. The upper end portion of the arm 48^a is preferably horizontally disposed and is deflected slightly so that it terminates above the nail throat or sleeve 31 and carries the upper end of the driving rod 32 therein as hereinbefore mentioned. In order to positively guide the outer end of the driving arm, I have mounted a suitable block 49 upon the adjacent side of the nail throat, said block having a vertically elongated groove 50 in the face thereof nearest said driving arm, and a suitable plate 51 is secured to said arm so that it projects a distance therefrom sufficient to permit its edge 45 to ride in said groove 50, thereby preventing lateral movement of the driving-arm during its operation. Mounted on arm 48^a adjacent the outer end of the upper horizontal member thereof is a suitable roller 52 that is adapted, during the vertical reciprocal movement of arm 48^a, to engage one and then the other of the members of an adjustable bell-crank 53, that is pivotally carried upon the boss, 44, just below the hopper block. This bell-crank has a bifurcated plate 54 connected to it, the bifurcations of which face upwardly and engage the switch operating lug 20 at the lower end of said hopper block, thus permitting the nail feed 55 to be operated to discharge a nail into the chute or feed pipe during each downward movement of the driving-arm.

The raceway 10 preferably forms a part of a nail-magazine or hopper that is carried upon the end of an arm projecting laterally

from a suitable bushing or collar 9 conveniently mounted upon a stub 8 arising from the upper end of standard 42 and capable of a slight vibratory movement. Mounted upon and movable with the boss 48 is a vertically disposed post 7, the upper end whereof is adapted to contact the lower flange of the bushing or collar 9 and thereby agitate the nails in the hopper or magazine and facilitate their feeding to the raceway.

While I have herein illustrated and described certain specific instrumentalities for carrying out my invention, it, of course, will be obvious to others skilled in the art to which it pertains, that divers modifications or refinements thereof are possible without materially departing from the spirit of my invention. I therefore desire it understood that all such changes and alterations are contemplated as included within the scope of my invention as expressed in the appended claims.

What I claim is:—

1. A nail feeding mechanism comprising, a nail conveying guideway, a disk disposed to rotate adjacent the discharge end of said guideway and provided with a slot adapted to receive the shank of a single nail, an apron depending from the periphery of said disk adjacent said slot, a second nail conveying guideway disposed adjacent said first mentioned guideway and having its upper end in the path of said disk, and ejector arms disposed parallel to each other and above and below said disk and in the path of the slotted portion thereof, so that the nail will be ejected from said slot when said disk is rotated to bring said nail above said second guideway.

2. In a nail-feeding mechanism, a rotatable disk provided with a notch adapted to receive a nail from a suitable nail guideway, an apron depending from said disk adjacent said notch, and an ejector provided with two arms arranged to extend above and below said disk and across the path of said notch.

3. In a nail feeding mechanism, a rotatable disk provided with a notch adapted to receive a nail from a suitable nail guideway, an apron depending from said disk adjacent said notch, and an ejector provided with two arms arranged to extend above and below said disk and across the path of said notch, the upper portion of said lower arm being beveled.

4. In a nail feeding mechanism, a rotatable disk provided with a notch adapted to receive a nail from a suitable nail guideway, and an ejector provided with two arms arranged to extend above and below said disk and across the path of said notch, and means for locking said disk against rotation.

5. In a nail feeding mechanism, a rotatable disk provided with a notch adapted to

- receive a nail from a suitable nail guideway, and an ejector provided with two arms adapted to extend above and below said disk and diagonally of the path of said notch, 5 and means for locking said disk against rotation comprising a peripheral recess in said disk, and a longitudinally reciprocable member to be introduced into and withdrawn from said recess.
10. 6. In shoe nailing machines, a reciprocal driving arm the outer portion whereof is provided with a vertical bore, a head mounted in said bore and having a longitudinal slot formed therein, a driving rod inserted in said slot and frictionally retained therein, a clamping bolt tapped transversely through said arm and engaging said slotted head, the arrangement being such that said head and said rod are secured in position, and a 15 nail-throat having an elongated central bore in which said driving rod reciprocates and is guided thereby.
7. In a shoe nailing machine, a standard provided with a lateral overhanging extension, a guide rod the ends whereof are mounted in said extension and the base of said standard respectively, a driving arm carried by and reciprocal on said guide rod, a plate mounted on said extension adjacent 20 the outer free end of said driving arm and provided with a vertical groove in its face nearest said arm, and a member arranged to project from the end of said driving arm and to enter and be guided in said groove 25 so that lateral movement of said arm is prevented.
8. In a shoe nailing machine, a standard provided with a lateral overhanging extension, a guide rod carried by said extension, 30 a driving arm mounted to reciprocate on said guide rod and the free outer end whereof terminates adjacent the outer portion of said extension, and coöperating devices on said extension and driving arm so arranged 35 that lateral movement of the latter is prevented.
9. In a shoe nailing machine, a standard provided with a lateral overhanging extension, a guide rod carried by said extension, 40 a driving arm mounted to reciprocate on said guide rod, the free outer ends of said arm terminating adjacent the outer portion of said extension, and coöperating devices on said extension and on the said end of the 45 driving arm consisting of a vertically elongated grooved plate and an elongated member engaging said grooved plate so that lateral movement of the driving arm is prevented.
50. 10. In a shoe nailing machine, a nail receptacle, a nail throat, a driving rod oper-
- able therein, means for separating and conducting the separated nails from said nail receptacle to said throat and including a removable nail chute adapted to receive the 55 separate nails from the separating means and discharge the same into said nail throat, and devices adapted to lock said nail separating means against operation.
11. In a shoe nailing machine, a nail receptacle, a feeder adapted to receive nails from said receptacle and discharge the same one at a time to the driving member, devices adapted to lock said feeder against operation, and a removable nail chute interposed 75 between said feeder and the driving member.
12. In a shoe nailing machine, a nail receptacle, a nailing member, a rotatable nail-feeding device coöperating with said receptacle, a chute adapted to receive nails from 80 said nail feeding device, and discharge the same to said nailing member, and a block carrying said nail feeding device and removably mounted on said machine and in which the upper portion of said chute is 85 mounted, the lower portion of said chute being removably inserted in a channel leading to the nailing chamber.
13. In a shoe nailing machine, a nail driving member, a nail receptacle, a rotatable 90 nail feeding device coöperating with said receptacle, a chute adapted to receive nails separately from said nail feeding device, a nail throat in which the nail driving member reciprocates and which is provided with 95 a nail chamber of the same diameter throughout its length and is continuous from the lower end of said chute to the nailing member within said throat, and means 100 adapted to lock said nail feeding device against operation.
14. In a shoe nailing machine, a nail driving member, a nail receptacle, a feeder adapted to receive nails from said receptacle and discharge same one at a time to the 105 driving member, devices adapted to lock said feeder against operation; a removable nail chute interposed between said feeder and driving member, and a nail throat in which 110 said driving member reciprocates and which is provided with a nail chamber of the same diameter throughout its length and is continuous from the lower end of said chute to the driving member within said throat.

Signed at St. Joseph, county of Buchanan, 115 and State of Missouri, this 6th day of October, 1916.

JAMES BRAGG.
